UNITED STATES PATENT OFFICE

HERMAN C. MUELLER, OF MILWAUKEE, WISCONSIN

SOUND-REPRODUCING DEVICE

Application filed October 21, 1926. Serial No. 143,103.

My invention relates to a loud speaker unit more especially intended for use in connection with radio reception; the invention having for its object the provision of a device 5 properly sensitive to the pulsations or actuating current changes and adapted to reproduce the tonal characteristics of the modulating medium, whether voice or instrument, employed at the broadcasting station.

Another object of my invention is the provision of a construction wherein the diaphragm is so constructed and mounted that it will be maintained under tension and 15 eliminate as far as possible any sympathetic and synchronized vibrations that may be set up and which will provide proper and natural tonal effect, while at the same time preventing possibility of the diaphragm becoming locked to either one of the pole pieces of the reproducer.

The above enumerated objects as well as other objects and advantages inherent in the construction will be readily comprehended 25 from the detailed description of the accompanying drawings, wherein—

Figure 1 is an elevation of a loud speaker or horn illustrating in dotted lines an application of my improved unit.

Figure 2 is a vertical sectional view of the unit and lower or base portion of a horn.

Figure 3 is a cross sectional view taken 35 on the line 3—3 of Figure 2 looking in the direction of the arrows.

Figure 4 is an end elevation of my improved unit with a portion of the housing or casing shown in section.

Figure 5 is an enlarged sectional view 40 taken substantially on the line 5—5 of Figure 4 looking in the direction of the arrows.

Figure 6 is a sectional view taken substantially on the line 6—6 of Figure 5 looking in the direction of the arrows.

Figure 7 is a detail perspective view of 45 a pole piece separating member and armature support holding member.

Figure 8 is a detail perspective view of 50 my improved armature.

In the particular exemplification of the invention as disclosed in the drawings, my improved loud speaker unit is shown applied to the well known type of horn 15, see Figure 1, with the unit indicated in 55 dotted lines at 16 mounted in the base portion and in communication with the small or receiving end of the horn. It will be understood, however, that my improved unit may be applied to any suitable shape or type 60 of horn or other sound amplifying device.

For purposes of illustration, my improved unit is mounted in the base, a portion of which is shown at 15^a in Figure 2, by having the externally threaded hub 17 of the 65 cover plate 18 screwed into the throat of the base portion of the horn in alignment with the inlet or small end of the horn. The cover plate or member 18, and the shell member 19, are preferably annular and of 70 suitable thickness to provide rigidity. These two members 18 and 19 are secured together by suitable means, as for example the screws 20. The cover member 18 is provided with a beveled circumferential groove 75 21, with the bevel formed so that the groove increases in depth toward the periphery of the cover member 18. The cover member is centrally provided with the outlet opening 22 which is preferably provided with 80 the usual screen indicated at 23 to prevent ingress of foreign matter.

The shell or annular member 19 is dished or cupped to provide a suitable chamber between it and the cover member 18 where- 85 in the diaphragm 24 is located; that is to say, the shell 19 is provided at its outer perimeter with an annular shoulder 25 which comes into abutting relation with the cover member 18; the main body portion of 90 the shell 19 being provided with a suitable number of openings 26 and with the large central opening 27 through which the stylus-bar 28 passes. The shell or member 19, ad- 95 jacent to the annular shoulder 25, is also provided with an annular beveled groove 29, which, like the groove 21, in cover member 18, increases in depth toward the outer perimeter or annular shoulder 25. The shell 19, at the inner perimeter of the groove 100

29, is preferably formed with an annular ridge as at 30, see Figure 5. The annular grooves 21 and 29 are intended to receive the flat gaskets 31, 31, preferably of rubber, which are mounted adjacent to the perimeter of the diaphragm 24, both on the upper and lower sides thereof. As a result of this construction, when the shell 19 and cover member 18 are secured together, the flat gaskets 10 will be forced toward the deeper portions of the grooves that is to say will be squeezed outwardly and uniformly about the entire perimeter of the diaphragm which has the effect or tendency to stretch the diaphragm 15 outwardly and consequently holds the diaphragm tightly. Mounting the diaphragm in the manner shown and described, will hold it under constant tension and the pitch of the diaphragm thus maintained. This 20 method of mounting at the same time prevents possibility of the diaphragm becoming "locked" to either one of the pole pieces.

I also prefer to have the diaphragm 24 circumferentially corrugated, as shown, 25 thereby permitting the use of a lighter diaphragm and one made of softer material than otherwise would be the case. The center of the diaphragm is preferably dished or concaved as shown at 32 where it is secured to the stylus bar 28.

A permanent magnet 33 is disposed beneath the shell 19 with the ends of the magnet provided with extensions or pole pieces 34, 34, of U-shape in cross-section, having 35 upstanding ends or lips 35 adapted to engage with the sides of the permanent magnet 33. The sides of the pole pieces, secured to the two ends of the permanent magnet, are disposed toward each other and 40 terminate in slight spaced relation as shown in Figures 2, 4, 5 and 6. The sides of the pole pieces are adapted to extend along opposite sides of a suitable electro-magnet or coil 36 which is preferably formed into the 45 oblong configuration shown in Figures 4 and 6. The electro-magnet or coil 36 is provided with a suitable insulating tube or core 37 formed to receive a member 38 shown in Figure 7. The member 38 is provided 50 with the bent sides 39, 39 which preferably extend slightly beyond the ends of the member as shown at 40 in Figure 7; and the member is transversely slotted as shown at 41. The extended ends 40 provide shoulders 55 for the sides of the pole pieces 34 and maintain their proper spaced relation; the pole pieces therefore maintain the plate 38 in position within the core of the electro-magnet or coil 36. This member constitutes a 60 pole piece separating member and armature support holding member.

With the member 38 formed as shown it is apparent that a small space or chamber between the member and one side of the insulating tube or core 37 is provided to re-

ceive the vibration element or armature 42 which is shown in detail in Figure 8.

The armature comprises a plate, preferably of the rectangular configuration shown and provided longitudinally with a depression or rigidifying surface 43 which acts as a stiffener and eliminates vibration being set up in the armature itself. One side of the armature 42 is provided with a bridge or feather 44 extending transversely of the armature. This feather 44 is made of comparatively thin sheet metal or other suitable material having depending ends 45, 45 which extend into slits in opposite sides of the armature as shown at 45^a in Figure 8, with one of the depending ends on the lower side of the armature bent laterally in one direction, while the other depending end is bent laterally in the opposite direction. This holds the bridge or feather in place without too rigidly holding the armature. The armature is placed beneath member 38 between the downwardly bent sides 39, 39, with the bridge or feather 44 inserted in the slit 41 from the lower side as viewed in Figure 7. As the body portion of the member 38 extends flush with one side of the insulating tube or core 37, see Figure 5, it is apparent that too far upward movement of the feather or bridge 44 through the slit 41 is impossible, with the result that the armature 42 is held in spaced relation with the member 38 and the opposite side of the insulating tube or core 37 and is thus free to oscillate or vibrate by reason of the minute play of the feather or bridge in the slit, the play between the feather and the armature due to the bending of the ends of the feather in opposite directions as previously described, as well as the flexibility of the bridge or feather. One end of the armature 42 is preferably provided with a projecting lip or portion 46 which is apertured at 46^a to receive the end of the stylus-bar 28 which may be soldered or otherwise immovably secured thereto.

The permanent magnet with the pole pieces and the electro-magnet or coil (mounted within the permanent magnet at the ends thereof), together with the armature and its mounting, are held in place against the shell 19 by means of a clamping bar 47 disposed transversely of one leg of the permanent magnet. The bar 47 is secured to the shell 19 by the screws 48, 48. The clamping bar 47 is provided with suitable binding posts 49, 49 to receive the wires or terminals 50, 50 which go to the output end of the receiving set: the binding posts 49, 49 being properly insulated from the clamping bar 47 by suitable insulating washers 51 and these posts on what may be termed the lower ends receive the leads 52, 52 from the electro-magnet or coil 36.

The stylus-bar 28, preferably adjacent to its point of attachment to the armature, is provided with a flattened portion, as at 53, see Figures 2 and 5, so as to provide a flexible point; the flattened portion being disposed substantially parallel with the side of the pole-piece 34, in order that the bar may flex in a direction substantially parallel with the armature.

10 I have shown what is believed to be the simplest embodiment of my invention and have described the same in terms employed merely as terms of description and not as terms of limitation, as structural modifications may be made without, however, departing from the spirit of my invention.

What I claim is:—

1. A device of the character described comprising a shell provided with a diaphragm, a permanent magnet mounted on the shell and provided with an opening through one end thereof, aligned pole pieces disposed wholly within the ends of the magnet and secured thereto in opposing and 25 slight spaced relation with each other, a coil disposed transversely within the opposing pole pieces and provided with a non-magnetic core arranged in alignment with the spacing between the pole pieces, a transversely slotted plate within the core of the magnet coil provided with extended ends disposed intermediate of opposing ends of the pole pieces to maintain the latter in spaced relation and to be supported in place 30 by said pole pieces, an armature provided with a transverse bridge mounted in the transverse slot of said plate for tiltably mounting the armature, one end of the armature being provided with an extension disposed beyond the inner sides of the pole pieces, and a stylus-bar secured to said extension and disposed through the opening in the leg of the permanent magnet and secured to said diaphragm.

45 2. In a device of the character described, a permanent magnet, pole pieces mounted wholly within the ends of the permanent magnet and in opposing relation with each other, the ends of the pole pieces having flanges for clamping the sides of the permanent magnet, a coil mounted within the pole pieces and disposed transversely of the permanent magnet, said coil being provided with a non-magnetic core, a supporting member arranged within the core of the coil and provided with a transverse slot, an armature provided with an upstanding feather adapted to enter the slot in said plate, one end of the armature being provided with an extension, and a stylus-bar secured to said extension.

50 3. A device of the character described, comprising a shell, a cover plate for said shell provided with an opening, the shell and cover plate being provided on their

opposing faces with outwardly beveled grooves, a diaphragm mounted between the shell and cover plate, yielding means disposed on opposite sides of the diaphragm adjacent to the perimeter thereof and seatable in said grooves whereby the diaphragm is maintained under constant tension, a permanent magnet mounted on the shell, pole pieces secured to the ends of the magnet in opposing relation with each other, a coil disposed within the pole pieces, an armature tiltably mounted in the coil, and a stylus-bar secured at one end to said armature and at the other end to said diaphragm.

4. In a device of the character described, an armature of thin sheet material provided with a rigidifying surface disposed lengthwise thereof, the opposite sides of the armature being slotted, a yieldable element arranged transversely of the armature with the ends thereof disposed through the slots in the armature and bent in lateral directions to permit tilting of the armature.

5. In a device of the character described, a permanent magnet, pole pieces secured to the ends of the magnet and disposed wholly within the latter, a coil mounted within the pole pieces transversely thereof and having a non-magnetic core, a non-magnetic plate having angularly disposed sides mounted within the core of the coil and having extended shoulders disposed between the opposing ends of the pole pieces, said plate being provided with a transverse slot, an armature of thin sheet material formed to prevent vibration in the body of the armature and having slots at opposite sides, a feather disposed transversely of the armature and adapted to enter the slots in said plate, the body of the feather being in spaced relation with the armature while the ends thereof are disposed through the slots in the armature and bent in lateral directions on the opposite face of the armature.

6. In a device of the character described, a shell, a cover plate for said shell, the shell and cover plate being formed to provide a diaphragm receiving chamber therebetween, a diaphragm of thin sheet material circumferentially corrugated intermediate of the axis and the perimeter thereof, and means intermediate of the shell, the cover plate and the perimeter of the diaphragm whereby the latter is placed under a stretching tension.

7. In a device of the character described, a shell provided with a peripheral shoulder, a cover plate having an outlet and provided with a peripheral shoulder adapted to seat on the shoulder of the shell, the shell and cover plate on their opposing faces adjacent to the shoulder being each provided with a beveled groove, a diaphragm of thin pliable material disposed between the shell and cover plate, and resilient means mount-

ed on opposite faces of the diaphragm at the perimeter thereof and seatable in the grooves of the shell and the cover plate whereby the diaphragm is maintained under tension.

8. A device of the character described, comprising a shell provided with a central opening and with a peripheral shoulder, a cover plate for said shell secured to said shoulder and having a central outlet opening, a circumferentially corrugated diaphragm of thin sheet tensile material having a dished center, means disposed between the shell, the cover plate and the perimeter of the diaphragm whereby the latter is maintained under constant tensile action, a permanent magnet mounted on the lower side of the shell and provided with an opening through one end thereof adapted to register with the opening in the shell and the axis of the diaphragm, pole pieces secured to the ends of the permanent magnet and disposed wholly therewithin, a coil mounted transversely within the pole pieces with the core in alignment with the spacing intermediate of the opposing ends of the pole pieces, an armature tiltably mounted at its center within the core of the coil, one end of the armature having an extension disposed beyond the inner sides of the pole pieces, and a stylus-bar secured to said armature extension and disposed through the opening in the permanent magnet and the shell and secured to the dished center of the diaphragm.

9. In a sound reproducing device, a magnet provided with opposing pole pieces arranged on the inner opposing faces of said magnet and of channel formation, said pole pieces being disposed wholly within the magnet and extending in the direction of the line of magnetic flux and arranged to provide a space between the opposing ends of said pole pieces, the base of the pole pieces at opposite sides being outwardly flanged to engage opposite faces of the magnet ends, a coil mounted in the pole pieces with its core aligned with the space between the opposing pole piece ends, and a rigidified armature tiltably mounted within said coil and having an extension between the opposing ends of said pole pieces.

10. In a sound reproducing device, a magnet, pole pieces disposed wholly within the magnet in aligned relation with each other so as to extend in the direction of the line of magnetic flux and to provide a space between the opposing ends of the pole pieces, a coil mounted in the pole pieces with its core aligned with the space between the pole pieces, a flanged spacing plate located in the coil core with the ends of the plate flanges arranged between the opposing pole pieces to maintain their spaced relation, an armature arranged in the core of said coil

adjacent to said plate with its end disposed into said space, and flexing means disposed transversely of the armature intermediate of its ends and mounted on said spacing plate so as to permit tilting movement of the armature.

11. In a sound reproducing device, a coil provided with a core, a transversely slotted plate in the core of the coil, an armature of thin sheet material provided with an upstanding flexing portion arranged transversely of the armature and adapted to seat in the slot of said plate to constitute a fulcrum for the armature, the armature being provided with a rigidifying surface disposed in a direction transversely of said upstanding portion.

12. In a device of the character described, a permanent magnet, pole pieces composed of sheet metal bent into U-shape with opposite ends of the base portions bent outwardly to engage with opposite sides of the respective pole ends of the magnet, said pole pieces being located wholly within the magnet adjacent to the ends with the pole pieces aligned with each other, a coil arranged within the pole pieces with its core aligned with the spacing between the ends of the pole pieces, a spacing plate located within the core and having extensions on its ends arranged between the opposing ends of the pole pieces whereby the latter are maintained in spaced relation and said plate held in place, and an armature tiltably mounted on said plate.

HERMAN C. MUELLER.
